UNITED STATES PATENT OFFICE.

JOSEPH MUNGER, OF WATERBURY, CONNECTICUT, ASSIGNOR TO THE
SCOVILL MANUFACTURING COMPANY, OF SAME PLACE.

GUDGEON FOR WINDOW-SHADE ROLLERS.

SPECIFICATION forming part of Letters Patent No. 298,611, dated May 13, 1884.

Application filed January 21, 1884. (No model.)

To all whom it may concern:

Be it known that I, JOSEPH MUNGER, of Waterbury, in the county of New Haven and State of Connecticut, have invented a new Improvement in Gudgeons for Window-Shade Rollers; and I do hereby declare the following, when taken in connection with accompanying drawings and the letters of reference marked thereon, to be a full, clear, and exact description of the same, and which said drawings constitute part of this specification, and represent, in—

Figure 1, a perspective view; Fig. 2, a central section; Fig. 3, a central section of the cup detached; Fig. 4, the flanged gudgeon detached; Fig. 5, the gudgeons attached to the roller; Figs. 6 and 7, modifications.

This invention relates to an improvement in gudgeons for window-shade rollers, and particularly to that class which are secured to the end of the roller, in contradistinction to those which are driven into a hole bored into the end of the roller. In the more general construction of this particular class of gudgeons the gudgeon has been cast as a projection from a plate fitted to be attached to the end of the roller, and this attachment has been made in some cases by holes through the plate, through which nails or screws are driven into the end of the roller. In other cases a ring has been applied to the end of the roller, having a flange projecting inward over the gudgeon-plate, this flanged ring serving to hold the gudgeon-plate to the roller; but in either of these constructions it is necessary that the end of the roller shall be cut in a perfect plane at right angles to the face of the roller, in order that the gudgeon may project in a direct axial line therefrom. Any deviation from such a right-angled plane will turn the gudgeon out of its axial line and cause it to work imperfectly. Again, such construction of the gudgeon-plate necessitates the cutting of the roller to an exact length, and if it be cut shorter than such exact length then there is no means of adjustment to bring the gudgeon into its proper relative position to the bracket, and the roller is useless for that particular window.

The object of my invention is the construction of a gudgeon in which the perfect axial

and concentric position shall be insured irrespective of the plane on which the end of the roller is cut, and also one which will allow some considerable variation in the length of the roller without interference with the proper working of the gudgeon, and it consists in a sheet-metal cup of a diameter corresponding substantially to the diameter of the roller, and so as to be set on over the end of the roller, the said cup having the gudgeon arranged and secured concentrically in its closed end, as more fully hereinafter described.

A is the cup-shaped body, which is struck from sheet metal, the internal diameter corresponding substantially to the diameter of the roller, and so as to closely fit when placed over its end. At the center is a perforation, *a*, corresponding to the diameter of the gudgeon, and around this opening the bottom of the cup is struck outward, so as to form a recess, *b*, upon the inside, as seen in Fig. 3.

d is the gudgeon, around the inner end of which a flange, *e*, is formed by upsetting the metal or otherwise, in diameter and thickness somewhat less than that of the recess *b* in the bottom of the cup. This gudgeon is passed through the hole *a* from the inside outward, the flange *e* set into the recess *b*, as seen in Fig. 2, and there soldered or otherwise permanently fixed in its position. The gudgeon is made from hard metal, and preferably from wire, upset in the usual manner of making headed rivets. This completes the gudgeon. It is attached by placing the cup open end onto the roller, as seen in Fig. 5. The sides of the cup locate the gudgeon with relation to the roller, and so that the face of the cup will stand at right angles to the axis of the roller irrespective of the shape of the end of the roller—that is, it may be cut at an angle, as seen in Fig. 5—yet the face from which the gudgeon projects is certain to be at right angles to the axis of the roll and the gudgeon to be concentric and in direct axial line; and should the roller be cut too short, then the cup will be set onto the roller only so far as to bring the face of the cup and the gudgeon into the proper relative position.

Instead of making the gudgeon from a headed rivet and introducing it through the

hole *a* in the end of the cup, so as to bring the head upon the inside of the cup, the gudgeon may be made with a projection, *f*, upon the opposite side of the flange, as seen in Fig. 6, 5 and that projection introduced through a central hole in the cup from the outside, as seen in Fig. 7, and there riveted down upon the inner side of the cup; but I prefer the first-described method of attachment.

10 I claim—

1. The cup *A*, constructed with a central hole, *a*, in its bottom, combined with the flanged gudgeon *d*, secured to said cup through said central hole, substantially as described.

2. The cup *A*, constructed with the central 15 recess, *b*, upon the inner side of its bottom, and with a central hole, *a*, therein, combined with the flanged gudgeon *d*, introduced through the said central hole, *a*, to bring its flange into said recess, and there secured, substantially as 20 described.

JOSEPH MUNGER.
